UNITED STATES PATENT OFFICE,

HARRISON B. BOZARD, OF HAMILTON, ONTARIO, CANADA, ASSIGNOR TO INTERNATIONAL HARVESTER COMPANY OF CANADA, LIMITED, A CORPORATION OF ONTARIO.

STEEL BEARING FOR DISKS.

1,328,787.

Specification of Letters Patent. Patented Jan. 20, 1920.

Application filed March 14, 1919. Serial No. 282,695.

To all whom it may concern:

Be it known that I, HARRISON B. BOZARD, a citizen of the United States, residing at Hamilton, in the county of Wentworth and 5 Province of Ontario, Dominion of Canada, have invented certain new and useful Improvements in Steel Bearings for Disks, of which the following is a full, clear, and exact specification.

10 This invention relates to an improvement in disk drills, and more particularly to that class of drills known as double disk.

The object of the invention is to provide improved bearings for drills which will take 15 up small space, are easily lubricated, and can be removed and replaced easily and quickly.

A further object is to provide a construction of bearing that is simple to manufacture, and because of the improved lubricating facilities will have a long life.

In the accompanying drawing I have illustrated one embodiment of my invention, and

25 Figure 1 shows a side elevation of a portion of a disk drill having my improved bearing thereon, a part of the disk being broken away;

Fig. 2 is a sectional view taken on line 30 2-2 of Fig. 1; and

Fig. 3 is a detail view showing the construction of the bearing blocks.

The frame 10 of the drill is of ordinary construction, and is provided with a depending arm or boot 11 which carries the 35 improved bearings.

The boot 11 is provided with an oil duct 12, which extends downwardly therein to a central oil chamber 13 formed at the lower 40 end of the boot. The oil chamber 13 is enlarged as clearly shown in Fig. 2, and extends somewhat below the center line of the bearing in order to provide a pocket in which small particles of grit and dirt, which 45 may work down through the oil duct, will be collected. The lower end of the boot has outwardly extending transverse openings 14, and the outer surfaces of the lower end of the boot are milled to provide a uniform 50 surface to contact with the disks whereby the disk blades will be properly fitted and lined up.

Bearing blocks 15 are secured to the lower end of the boot by means of a transversely

extending bolt 16, the blocks being provided 55 with central apertures 17, generally square in outline, and having cut-away portions 18 to allow for the passage of oil outwardly from the central bearing chamber to oil retaining pockets hereinafter described. The 60 bolt 16 is formed adjacent its outer ends with squared portions 19, which engage with the squared opening in the bearing blocks, and prevent the rotation of these blocks. If desired, washers 20 may be interposed between the bearing blocks and the boot in order to properly space the blocks, and to 65 secure a proper bearing contact between the blocks and the disks. The disks 21 overlap the outer portions of the bearing blocks, as 70 shown at 22, and have a bearing contact therewith, the disks and blocks preferably being formed of hardened steel. Housings 23 are secured to the disks, as shown in Fig. 2, and these housings are spaced from the 75 central apertures of the disks, extend outwardly, and have bearing contact with the blocks 19, as shown at 24. The housings are formed with central screw-threaded apertures 25, which are closed by means of suitable plugs 26.

As illustrated in Fig. 2, annular pockets 27 are formed between the outer walls of the housings 23 and the bearing blocks 15, these 80 pockets being provided to retain a supply of lubricant which flows outwardly from the central chamber 13. Special attention is directed to the construction of these pockets, this construction being of great practical 85 importance. As described above, the disks 21 have a bearing contact with the bearing blocks 15, as shown at 22, the reference character 28 indicating the inner limit of 90 this bearing contact. This point of contact may be termed the live joint, where the oil which is being used to lubricate the bearing can escape. It will be observed that the oil illustrated in the oil pockets 27 in Fig. 2 is disposed below a plane passing through 95 these live joints indicated at 28; therefore, a supply of oil will be always available to 100 lubricate the bearing between the disks and the blocks 15, and between the housings and the blocks 15.

In the ordinary construction, provision 105 has not been made to provide a pocket of such dimensions that a supply of oil will be retained, and so arranged that the oil will

not escape through the live joints of the bearing.

It is believed that the operation of the construction will be clear from the above description, but the following brief outline of the operation is given.

The lubricant is supplied to the oil duct 12 in the boot 11, and flows downwardly through this duct to the central chamber 13.

- 10 From this chamber it passes outwardly at each side through the cut-away portions 18 of the bearing blocks to the pockets formed between the housings 23 and the bearing blocks. As stated above, the oil tends to 15 flow to the outer portions of the pockets, but owing to the fact that the pockets extend below the live joint, or the inner point of bearing contact between the disks and the bearing blocks, a supply of oil is always available, and the supply does not escape through 20 the live joints.

From the above description, it will also be seen that it is a very simple matter to assemble and disassemble this bearing, it being merely necessary to remove one of the 25 plugs 26, and by means of a wrench inserted through the aperture of the housing to remove the nut carried by the bolt 14. When this nut has been removed the bearing may 30 be taken apart without further trouble.

While I have, in the above specification, shown one embodiment of my invention, it is to be understood that the invention is capable of modification. Changes, therefore, in the construction and arrangement of 35 parts may be made without departing from the spirit and scope of the invention as disclosed in the appended claims.

Claims:

- 40 1. In a disk drill, the combination with a support, of a pair of disks having bearing contact with said support, and a pair of housings having oil pockets therein extending below the inner points of bearing contact between said support and said disks.
- 45 2. In a disk drill, the combination of a support, bearing blocks carried by said support, a pair of disks having bearing contact with said blocks, and a pair of housings carried by said disks and inclosing said bearing blocks, said housings having pockets therein between the walls of said housings and said blocks, said pockets extending below

the inner point of bearing contact between said disks and said blocks.

55

3. In a disk drill, the combination of a support having an oil duct therein and a central oil chamber at the lower end of said duct, said support having outwardly directed apertures leading from said oil chamber, a pair of bearing blocks secured to said support and having apertures registering with the apertures of said support, a pair of disks having bearing contact with said blocks, said disks carrying a pair of housings inclosing said bearing blocks and having pockets therein between the outer walls of said housings and said blocks, said blocks being provided with oil passages leading from the central oil chamber to said pockets.

60

4. In a disk drill, a support having an oil duct leading to a central oil chamber, said support having outwardly directed apertures leading from said oil chamber, bearing blocks secured to said support and having apertures registering with the apertures of said support, a pair of disks having bearing contact with said blocks, single means for securing said blocks to said support, housings carried by said disks and inclosing said blocks, said housings having apertures formed therein between the outer walls thereof and said blocks, said pockets extending below the inner points of bearing contact between said disks and said blocks.

65

5. In a disk drill, a support having an oil chamber therein, and an oil duct leading to said chamber, said support having outwardly directed apertures, bearing blocks secured to said support and having apertures registering with the apertures of said support, single means for securing said bearing blocks to said support, said blocks being provided with oil passages leading to said central chamber, a pair of disks having bearing contact with said blocks, housings carried by said disks and inclosing said blocks, said housings having pockets therein extending below the points of bearing contact between said blocks and said disks.
